PRESSER MEMBER FOR CLICKING
MACHINESMieth Maeser, Beverly, Mass., assignor to United
Shoe Machinery Corporation, Borough of Flem-
ington, N. J., a corporation of New Jersey

Application July 2, 1938, Serial No. 217,240

9 Claims. (Cl. 164—23)

This invention relates to machines for cutting blanks from sheet material and is herein illustrated in connection with a clicking machine of the type illustrated in United States Letters Patent No. 1,629,870, granted May 24, 1927, upon an application filed in the name of P. J. Horgan.

Machines of the type referred to are provided with a presser member adapted to be swung laterally over a cutting block or bed into operative relation to a freely movable die located upon sheet material positioned upon the block, the member being movable in a heightwise direction to force the die through the material to produce a blank. The machine disclosed in the patent referred to is provided with a presser member composed of light metal in order to minimize the effort required of an operator in swinging the member over the cutting bed and in stopping it in operative position over the work.

It is an object of the present invention to provide an improved presser member, for machines of the type referred to, so constructed that the effort required to swing it over the cutting block as well as to arrest its movement is still further reduced. To this end and as shown, I have provided a presser member, preferably composed of an alloy of a light metal such as aluminum, having the greater portion of its mass located near its axis of rotation and having reinforcing ribs so constructed and arranged as to provide adequate stiffness to the member and to transmit the forces caused by applied loads to the more massive portions of the same.

These and other features of the invention are disclosed in the following detailed specification and in the accompanying drawings and will be pointed out in the claims.

In the drawings:

Fig. 1 is a view in side elevation of a portion of a clicking machine embodying my invention;

Fig. 2 is a plan view of the body portion of the presser member;

Fig. 3 is a perspective view partly in cross section of the body portion of the presser member; and

Figs. 4, 5, 6 and 7 are cross sectional views taken along lines IV—IV, V—V, VI—VI and VII—VII, respectively, of Fig. 2.

As shown in Fig. 1, the invention is embodied in a clicking machine having a frame 10 in which is mounted a spindle 12 arranged for rotation about its axis and for movement in a heightwise direction, there being a presser member or arm 14 secured to the spindle and arranged for movement laterally across the surface of the cut-

ting block 16 and for movement with the spindle heightwise thereof. The presser member 14 comprises a body portion 18, an end of which engages the spindle, and a cap 20 partially surrounding the spindle and secured thereto by means of U-bolts 22 and 24.

The body portion of the presser member is a box-like integral casting preferably of an alloy of a light metal such as aluminum and has at one end thereof semi-cylindrical portions 26 which constitute bearings for engagement with the spindle 12. Extending from the lower cylindrical portion 26 is a flat base portion or plate 28 which is narrow near the spindle but flares outwardly thereof to form a substantially rectangular plate. Extending from the base plate 28 longitudinally thereof is a central reinforcing wall or partition in the form of a vertical plate 30. The plate 30 is cut away to form openings 32 and 34 leaving struts 36 and 38 extending between the base plate and a top plate 39 as well as ribs 40 along the under side of the top plate and ribs 42 along the upper surface of the base plate. This construction makes for lightness but at the same time provides adequate strength. There are provided two side walls in the form of plates 44 which extend from the bearings 26 diverging outwardly along the base plate and substantially perpendicular thereto. The side plates 44 are cut away, as shown at 46 and 48, to lighten the structure, leaving large ribbed portions 50 and 52 extending along the top and base plates. The side plates adjacent to the bearings are solid in order to provide adequate strength near the spindle where maximum bending moment takes place. The central and side plates gradually decrease in height, outwardly of the spindle, and support the top plate 39. The top plate 39 is inclined downwardly and outwardly from the upper bearing 26 and is split at its lower end to form forked portions 54 which curve downwardly and outwardly along the base plate to provide clearance for a handle 56 operatively connected to a clutch control mechanism, not shown. The top plate 39 is in the form of an arch with the thickness of the plate at a maximum near the spindle and decreasing gradually toward its lower end to a thickness substantially as thin as can be cast. This construction is such that a load applied against the bottom of the base plate at the end thereof will be transmitted directly through the top plate to the spindle.

The base plate 28 has its upper face beveled outwardly as at 55 from the side plates 44 to its peripheral edges. The central portions of the 55

upper surface of the base plate are dished, as shown at 58, Figs. 4, 5, and 6, between each of the side plates 44 and the central plate 30. This provides an inverted arch construction which contributes materially to the lateral stiffness of the base plate. The base plate is further strengthened by means of a removable striking plate 60 which is secured to the under side of the base plate by means of bolts 62. Preferably this striking plate and the bolts are of the same composition as the body portion of the arm which thus contributes to lightness and at the same time will form a comparatively soft striking face which will not dull the edges of double-edged dies used in the machine, and which can readily be replaced when it becomes worn.

In order further to reinforce the body portion of the arm I have provided ribs 64 extending at a sharp inclination to the central plate and outwardly to the side plates. I have provided similar ribs 66 extending from the central plate to the side plates and upwardly along the latter and then along the top plate back to the central plate. These ribs serve to stiffen the base plate and to prevent the top plate from buckling. They further serve to transmit pressure due to a load applied to the striking plate toward the central portion of the arm and in a rearward direction, thereby to cause the forces to traverse a path along the central plate toward the spindle where the greater portion of the mass of the arm is concentrated. There are additional ribs 68 extending from the central plate along the top plate and toward the side plates at points where the side plates are solid, there being vertical ribs 70 extending along the side plates for a further reinforcement. Ribs 72 extend along the base plate from the central plate 30 to bosses 74 in which the U-bolts 24 are received. The top plate 39 is further stiffened near the bearing 26 by ribs 76.

In the operation of the machine, the arm 14 is swung in the usual manner about the axis of rotation of the spindle 12 into position over a die located on sheet material carried by the block 16 and is then depressed to force the die through the material to produce a blank. The construction above described is such that a load applied to the under side of the striking plate 60 will be transmitted through the more massive central and inner portions of the arm to the spindle with the result that the arm has great strength and rigidity in comparison to its weight. Furthermore, because of its light construction and because of the fact that the greater part of the mass of the arm is concentrated near the axis of rotation, the arm can be swung laterally across the block with little effort, and can be readily stopped in operative position over the work.

Having described my invention, what I claim as new and desire to secure by Letters Patent of the United States is:

1. A hollow unitary presser member for a clicking machine comprising a shell cast in one piece and having a base portion, a top wall extending upwardly from the base portion, side walls extending between the base portion and the top wall, and a central reinforcing wall connecting the base portion and the top wall and partitioning the presser member longitudinally.

2. A hollow unitary presser member for a clicking machine comprising a shell cast in one piece and having a base portion, a top wall extending at an inclination to the base portion, side walls

extending between the base portion and the top wall, a central reinforcing wall connecting the base portion and the top wall and partitioning the presser member longitudinally, and reinforcing ribs upon opposite sides of the central wall 5 and extending along the inner faces of the top and side walls and the base portion.

3. A presser member for a clicking machine comprising a hollow shell having a base portion, a top wall extending at an inclination to the 10 base portion, central and side walls extending between the top wall and the base portion, and reinforcing ribs extending about the inner faces of the top and side walls and the base portion at an inclination to the central wall for transmitting forces applied to the base portion in directions rearwardly of the central wall.

4. A presser member for a clicking machine comprising a hollow casting having a bearing portion, a base portion, a top wall extending outwardly from the bearing portion to the outer part of the base portion, central and side walls joining the top wall and the base portion, and reinforcing ribs extending at inclinations to each other on opposite sides of the central wall and 20 connecting the central wall to the side walls.

5. A presser member for a clicking machine comprising a hollow casting having a bearing portion, a base portion extending outwardly from the bearing portion, central and side walls extending outwardly from the bearing portion along the base portion, the base portion being dished between the central and side walls to form inverted arches for strengthening the 30 presser member in a transverse direction. 35

6. A presser member for a clicking machine comprising a hollow casting having a bearing portion, a base portion extending outwardly from the bearing portion, an upstanding wall extending outwardly from the bearing portion along 40 the base portion, and ribs extending along the base portion at inclinations to the upstanding wall for transmitting forces applied to the base portion rearwardly toward the bearing portion.

7. A presser member for a clicking machine 45 comprising a casting having a bearing portion, a base portion extending outwardly from the bearing portion, and an arched wall extending outwardly from the bearing portion of the outer end of the base portion for transmitting forces 50 applied to the base portion toward the bearing portion, the arched wall being of decreasing thickness outwardly of the bearing portion.

8. A presser member for clicking machines comprising an integral casting having a base 55 plate, a top plate extending at an inclination to the base plate, central and top plates extending between the top plate and the base plate, and reinforcing ribs extending along the top plate, a side plate and the base plate and lying substantially in planes extending at an inclination to the central plate for transmitting in directions rearwardly of the central plate forces applied to the base plate.

9. A presser member for clicking machines 65 comprising an integral casting having a base plate, a top plate inclined relatively to the base plate, central and side plates extending between the base plate and the top plate, and reinforcing ribs extending from the central plate along the top plate, one of the side plates and the bottom plate at an inclination to the central plate. 70

CERTIFICATE OF CORRECTION.

Patent No. 2,181,903.

December 5, 1939.

MIETH MAESER.

It is hereby certified that error appears in the printed specification of the above numbered patent requiring correction as follows: Page 2, second column, line 49, claim 7, for "portion of" read --portion to--; and that the said Letters Patent should be read with this correction therein that the same may conform to the record of the case in the Patent Office.

Signed and sealed this 10th day of September, A. D. 1940.

(Seal)

Leslie Frazer,
Acting Commissioner of Patents.
